E. HILL, Inventor
By Atty.
John E. Earle.

UNITED STATES PATENT OFFICE.

EBENEZER HILL, OF SOUTH NORWALK, CONNECTICUT.

CROSS-HEAD.

SPECIFICATION forming part of Letters Patent No. 373,661, dated November 22, 1887.

Application filed May 23, 1887. Serial No. 239,168. (No model.)

To all whom it may concern:

Be it known that I, EBENEZER HILL, of South Norwalk, in the county of Fairfield and State of Connecticut, have invented a new Improvement in Cross-Heads; and I do hereby declare the following, when taken in connection with accompanying drawings and the letters of reference marked thereon, to be a full, clear, and exact description of the same, and to which said drawings constitute part of this specification, and represent, in—

Figure 1, a top view of the cross head complete; Fig. 2, an aside view of the same; Fig. 3, an under side view of the same; Fig. 4, a vertical section through the cross-head and socket in the longitudinal central line of the pistons; Fig. 5, a horizontal section through the piston-rod and socket, illustrating the key adjustment; Fig. 6, a section through the socket at right angles to the section in Fig. 4; Fig. 7, a modification.

This invention relates to an improvement in that class of cross-heads which are adapted for the use of two connecting-rods extending to two cranks on the same shaft, and while applicable to steam-engines in which such an arrangement of rods exists, it is particularly applicable to the class of machines known as "compound air-compressors"—that is to say, air-compressors employing two cylinders in the same longitudinal line, the cross-head being arranged in longitudinal guides between the cylinders, and the piston-rods of the respective cylinders connected to the cross-head upon its opposite sides, the cross-head extending to the right and left through said guides, the ends of the connecting-rods by which reciprocating movement is imparted to the cross-head being applied one to each end of the cross-head, thus connecting the cross-head to two cranks upon the same shaft—a construction of air-compressor common and well known, and does not require particular illustration or description.

My invention relates particularly to the means for connecting the piston-rods to the cross-head, whereby convenience in take up and adjustment is attained.

A represents the cross-head, which is of usual shape, and is constructed with a trunnion, B, upon each end, by which the two connecting-rods are hung to it also in the usual

manner. Through the cross-head, in a plane parallel with the plane in which the pistons move, is a recess, C. In this recess the piston-rod socket D is arranged. This socket is 55 less in thickness than the height of the opening, as seen in Fig. 4, so that the socket may stand free in said recess for movement up or down. Vertically or at right angles to the socket a pin, E, is introduced through the socket 60 and rigidly held in the cross-head, so as to be substantially a fixed part of the cross-head. The socket is constructed with a vertical opening of larger diameter than the pin E, and so that the pin extending through the opening in 65 the socket permits a limited amount of freedom between the socket and pin. The two ends of the socket D are constructed to receive the end of the respective rods, F G, the openings for the end of the rods extending through to 70 the pin-opening, and that end of the two rods is constructed of a shape corresponding to the shape of the pin E, and so as to bear against the pin, as seen in Figs. 4 and 5. Transversely through the socket, at each side of the pin, a 75 key-hole, H, is formed, which key-hole is in substantially the central plane of the respective piston-rods, and each piston-rod constructed with a corresponding key-hole, I. (See Fig. 4.) Through these key-holes keys J 80 are driven, adapted to take a bearing upon the outer end of the key-holes in the socket and the inner end of the key-holes in the rods, as seen in Fig. 5, the keys being tapering. The driving in of the keys tends to force the rods 85 toward the pin and bring their respective ends to a hard bearing against the pin E, as indicated in Fig. 5. These keys through the two rods permit the adjustment of the cross-head in relation to the two rods, as may be required. The socket is made adjustable vertically in its recess around the pin E by set-screws K and L, one through one side of the cross-head and the other through the opposite side, adapted to bear upon the respective faces 90 of the socket, as seen in Fig. 2, and so that by means of the set-screws the socket may be raised or lowered with relation to the cross-head, as occasion may require. Thus I provide a substantially universal adjustment of 95 the socket and piston-rods with relation to the cross head, and yet leave the socket substan-

tially free upon the pin in the cross-head. The vertical adjustment of the cross-head by means of the set-screws K L may be omitted and the longitudinal adjustment of the socket only retained. The key-holes through the rods and through the sockets, with the keys introduced, are a common means of adjustment, and for this may be substituted other equally well-known means, as a nut. (Represented in Fig. 7.)

10 I claim—

1. In a cross-head substantially such as described, having an opening in the plane of the piston- rods, the combination therewith of a pin through said recess, a socket arranged in said recess upon said pin, the opening through the socket being larger than the diameter of the pin, the said socket constructed upon opposite ends with an opening extending inward to the said pin, two piston- rods extending, respectively, into the end openings in the socket, and the inner ends of the said piston- rods both resting against the said pin, and adjusting devices, substantially such as described, between the said socket and the said two piston- rods, respectively, substantially as described, and whereby the cross- head is made adjustable with relation to the two rods without changing the relation of the rods to each other.

2. In a cross-head substantially such as de-

scribed, having an opening through it in the plane of the piston- rods, the combination therewith of a pin through said recess, a socket arranged in said recess upon the said pin, piston- rods, one secured to each end of said socket, said socket made vertically adjustable in the recess in the cross-head, substantially as described.

3. In a cross-head substantially such as described, having an opening in the plane of the piston- rods, the combination therewith of a pin through said recess, a socket arranged in said recess loosely upon said pin, the said socket constructed upon opposite ends with an opening extending inward to the said pin, two piston- rods extending, respectively, into the end openings in the socket and adapted to bear upon the said pin, the socket and rods constructed with corresponding key- openings, with keys through said openings, and set-screws in said cross-head adapted to bear upon opposite sides of said socket, and whereby said socket is made vertically adjustable in the recess in the cross- head, substantially as described.

EBENEZER HILL.
